UNITED STATES PATENT OFFICE

LEWIS C. MARSHALL, OF WALPOLE, MASSACHUSETTS, ASSIGNOR, BY MESNE ASSIGNMENTS, TO THE SIMPLEX PISTON RING COMPANY OF AMERICA, INC., OF CLEVELAND, OHIO, A CORPORATION OF OHIO

PISTON PACKING FOR INTERNAL COMBUSTION ENGINES

Application filed April 14, 1924. Serial No. 706,261.

This invention pertains to metallic piston packing and more particularly to split ring packings of the type employed in internal combustion engines.

Principal objects of the invention are to provide an improved packing of simple and durable type applicable to pistons of the usual form employed in internal combustion engines, such pistons being of integral one-piece construction and provided with circumferential packing grooves of fixed width and substantially rectangular section; to provide a packing which without unusual difficulty or the employment of unusual tools may be installed in such piston grooves; and to provide a packing capable in an efficient manner of preventing gas leakage or oil pumping even at extremely high rates of reciprocation but without imposing excessive frictional pressure upon the cylinder walls.

With the above objects in view, the present invention comprises in brief the provision of a unitary main ring which is inherently resilient in an axial direction and which is adapted to bear with resilient pressure against the side walls of the piston groove, together with a follower or expander ring for forcing the main ring outwardly against the cylinder wall. While the main ring is radially as well as axially resilient the follower ring, which may be of more resilient material, for example, tempered steel, is of utility in supplementing the inherent expansive force of the main ring and at the same time provides for breaking or covering the joint or split in the main ring. Furthermore, it is preferred although not essential, to provide the main and expander rings with co-operating engaging surfaces so constructed that a component of the expansive force of the expander ring is directed axially to assist the main ring in maintaining its pressure upon the side walls of the piston groove.

In the accompanying drawing a preferred embodiment of the invention together with desirable modifications thereof is illustrated by way of example.

In the accompanying drawing, Fig. 1 is a perspective view of a piston packing em-

bodying the present invention in its preferred form;

Fig. 2 is a fragmentary radial section showing the preferred packing seated in the groove of the piston of an internal combustion engine;

Figs. 3 to 9 inclusive are fragmentary sections similar to Fig. 2, but illustrating modified embodiments of the invention;

Fig. 10 is a fragmentary development of the main ring of the improved packing, showing a modified arrangement of the dividing slot therein;

Fig. 11 is a view similar to Fig. 10, showing a further modified arrangement of the dividing slot; and

Fig. 12 is a similar view, showing a further modified arrangement of the slits in the ring, together with another arrangement of the dividing slot.

Referring to the drawing, the numeral 1 designates the main packing ring and the numeral 2 the auxiliary or expander ring. The main ring 1 is provided with a transverse gap at the point 3 preferably in such a manner as to provide a broken joint, while ring 2 is provided at the point 4, the gaps in the two rings being staggered in the usual manner.

The main ring 1 is provided with plain parallel radial surfaces and is of unitary construction consisting of a single annular turn of uniform width which may be made in accordance with any of the usual methods used in making split piston rings. This main ring is furnished with a plurality of series of circumferentially extending slits, the slits of one series being indicated by the numeral 5 and those of the other series by the numeral 6. The slits of the two series are arranged in staggered relation, the solid separating portion of the ring between adjacent slits of each series being substantially opposite to the center of a slit of the opposite series with the result that the ring is elastic, that is to say, readily compressible and expandable, in an axial direction. One slit of one of the series, for example the series 5, is preferably so arranged as to be substantially bisected in length by the gap 3 so that open ended slits of

70

75

80

100

substantially half the normal length extend oppositely from the gap. The corresponding solid separating portion of the ring is also intersected by the gap. Thus when the ends of the ring are brought together the slits and solid separating portions extend in substantially symmetrical series about the entire circumference of the ring. The ring is preferably of a width substantially equal to or slightly greater than that of the groove in the piston in which it is to be installed.

Referring to Fig. 2, the numeral 7 indicates the piston of an internal combustion engine having the usual packing groove 8. As ordinarily constructed, such a piston is of one piece integral formation, and the packing grooves are turned in the circumferential surface of the piston, such grooves having substantially parallel plain side walls 9 and 10, which occupy a fixed and unvarying position relative to each other.

In this figure the main ring 1 is shown as seated in the piston groove 8, with its end faces bearing against the side walls 9 and 10 of the groove.

While the main ring 1 is inherently elastic, both in an axial and in a radial direction, it is found to be desirable to supplement the elasticity of the main ring by means of an auxiliary ring which may be of more resilient material, such for example as tempered steel. In accordance with the simple structure arrangement illustrated in Figs. 1 and 2, a single expander ring 2 provides the desired added elasticity for the main ring, both in an axial and also in a radial direction.

The main ring 10 is furnished with a groove 11 symmetrically disposed in its inner peripheral surface and preferably the opposite side walls 12 and 13 of this groove are arranged in converging relationship. In the preferred arrangement, these walls are substantially flat and converge toward the outer surface of the ring, the spring expander ring 2 being furnished with corresponding inclined end faces which engage the surfaces 12 and 13 of the main ring, thus tending to expand the main ring both in an axial direction and in a radial direction.

In the preferred arrangement, the ring 2 is of a thickness such that it seats wholly within the groove 11 of the main ring, so that the piston groove 8 need not be of unusual depth.

In Fig. 3 the main ring is of substantially the same construction as shown in Figs. 1 and 2, but the auxiliary ring 14 is provided with a curved surface bearing against the inclined walls 12 and 13 of the groove 11 of the main ring. This form of expander ring is somewhat simpler to construct than that shown in Fig. 2, and may be substituted therefor, if desired, the operation of the expander ring 14 being similar to that of the expander ring 2.

In Fig. 4 a further modified arrangement is illustrated, the main ring 1^a being slightly different from the ring 1 shown in the preceding figures, in that the bottom wall of its groove 11 is substantially parallel to its end face, instead of being inclined. This bottom wall 15 co-operates with the radial end face of the auxiliary ring 16, the opposite end face of said ring being inclined for engagement with the inclined surface 12 of the main ring. This arrangement functions in substantially the same manner as those just previously described, although the axial component of the pressure of the expander ring may be somewhat less pronounced.

In Fig. 5 a still further modification is shown wherein the main ring 1^b is provided with a single inclined inner face 17 instead of the groove 11. A wire expander ring 18 bears against the surface 17 and tends to move the main ring radially outward and also to compress said ring against the upper wall 9 of the piston groove.

In Fig. 6 a further modification is illustrated, wherein the main ring 1^c is of simple rectangular section having a plain cylindrical inner wall 19 which is engaged by a plain expander ring 20. In this arrangement the expander ring exerts no axial component of pressure against the main ring, the inherent elasticity of the latter being depended upon for securing the desired pressure against the side walls of the piston groove.

In Fig. 7 a still further modification is shown in which the main ring 1^d is furnished with a groove 21 of curved section in its inner peripheral surface for the reception of a round expander ring 22. In this arrangement as in that of Fig. 6 the expander ring merely reacts in a radial direction against the main ring.

In Fig. 8 the main ring 1^e is furnished with an undercut groove 23 in its outer face for interlocking engagement with a bearing ring 24 adapted to engage the cylinder wall. A plain expander ring 25 bears against the inner face of the main ring tending to expand the latter radially. In this arrangement the bearing ring 24 takes up the wear against the cylinder wall and may readily be replaced without renewing the entire ring. The bearing ring 24 must necessarily have a clearance in the slot 23 to permit the proper compression and expansion of the main ring 1^e.

In Fig. 9 a further modified arrangement is shown in which the main ring 1^f is furnished with an undercut groove 26 in its inner wall, such groove having opposite converging end faces 27 and 28 respectively for engagement with inclined end faces of an expander ring 29 having interlocking engagement with the groove 26. The operation of this modified form is substantially like that shown in Fig. 2 except for the fact that the

expander ring is interlocking with the main ring so that the parts are not readily separated.

5 In Fig. 10 the main ring 1^g is shown as provided with an inclined dividing slot 30 instead of the arrangement shown in Fig. 1.

In Fig. 11 the main ring 1^h is shown as provided with a dividing slot comprising the axial recesses 31 and 31^a connected by the circumferential slot 32, the adjacent ends of both series of slits 5 and 6 being closed.

10 In Fig. 12 a further modified arrangement of the slits is shown in which the slits 5 and 6 are furnished with axially extending branches 5^a and 6^a respectively. This arrangement makes the ring extremely elastic and by providing a passage 33 into one of the slits, for example the slit 5, a ready means is provided for dividing the ring.

15 The ring above described in any of its specific modifications is found to be highly efficient as a packing in preventing the leakage of gas and pumping of oil, even at the highest speeds of reciprocations to which the piston may be subjected. The packing thus provided is of simple form and can be manufactured at relatively low cost, its parts do not tend relatively to separate when out of the piston groove and it requires no change in the shape or size of the piston groove usually furnished for its installation.

20 While certain specific modification of the invention are shown and described, it is to be understood that these are merely illustrative of the many modifications in which the broad invention may be embodied.

I claim:

25 1. The combination with relatively reciprocating members, one of which has an annular groove therein, of a trans-split ring peripherally insertable in said groove, said ring being circumferentially slotted to form an axially flexible portion integrally connecting opposite side portions, and auxiliary resilient means reacting upon said side portions to hold the same in sealing contact with the side walls of the groove and with a predetermined pressure limited to permit radial movement of the ring in the groove under working conditions.

30 2. The combination with relatively reciprocating members, one of which has an annular groove therein, of a trans-split ring peripherally insertable in said groove, said ring being circumferentially slotted to form an axially flexible portion integrally connecting opposite side portions, and a radial expander reacting upon said opposite side portions of the ring to hold the same in sealing contact with the side walls of the groove and with a predetermined pressure limited to permit radial movement of the ring in the groove under working conditions.

35 3. The combination with relatively reciprocating members one of which has an annu-

lar groove therein, of a trans-split ring peripherally insertable in said groove, said ring being circumferentially slotted to form an axially flexible portion integrally connecting opposite side portions, and a resilient expander reacting upon said ring with a force having radial and axial components, the latter holding said opposite side portions in sealing contact with the side walls of the groove and with a predetermined pressure limited to permit radial movement of the ring in the groove under working conditions.

4. The combination with relatively reciprocating members, one of which has an annular groove therein, of a trans-split ring peripherally insertable in said groove, said ring being circumferentially slotted to form an axially flexible portion integrally connecting opposite side portions and having a groove at its inner peripheral face and a resilient expander engaging the groove in said ring and reacting thereon with a force having radial and axial components, the latter holding said opposite side portions in sealing contact with the sides of the groove and with a predetermined pressure limited to permit radial movement of the ring in said groove under working conditions, said radial component coacting with the radial expansion of the ring to maintain peripheral sealing contact.

5. In a one-piece piston packing ring having an upper and lower series of staggered slots extending through the ring, said ring being thinner at the center line between its axial faces at the inside circumference of the ring and forming inner projecting circumferential edges, an inner re-enforcing ring made of thin and substantially wide spring material exerting pressure only at the inner projecting circumferential edges.

6. A piston ring having a plurality of overlapping slots extending therethrough and provided in its inner side with an annular groove with oppositely disposed inclined walls; and an expanding ring disposed within said groove and coacting with said inclined walls to expand said ring diametrically and laterally.

Signed at Boston, Massachusetts, this 11th day of April, 1924.
